(57) **CLAIM**

I claim the ornamental design for a figurine, as shown and described.

DESCRIPTION

FIG. 1 is a perspective view of a figurine showing my new design in a posture position;

FIG. 2 is a front elevation view of a figurine, illustrated in a neutral posture position;

FIG. 3 is a rear elevation view of FIG. 2;

FIG. 4 is a right-side elevation view of FIG. 2, the left-side elevation view being a mirror image thereof;

FIG. 5 is a top plan view of FIG. 2; and,

FIG. 6 is a bottom plan view of FIG. 2.
